L. VECCHIO

FUSE PLUG

Filed June 25, 1920

UNITED STATES PATENT OFFICE.

LUIGI VECCHIO, OF SCHENECTADY, NEW YORK, ASSIGNOR TO ELECTRICAL INVENTIONS & DEVELOPMENT COMPANY, OF SCHENECTADY, NEW YORK, A CORPORATION OF NEW YORK.

FUSE PLUG.

Application filed June 25, 1920. Serial No. 391,595.

To all whom it may concern:

Be it known that I, LUIGI VECCHIO, a subject of the King of Italy, residing at Schenectady, in the county of Schenectady and State of New York, have invented a new and useful Fuse Plug, of which the following is a specification.

This invention is a thermal cut-out device for electric circuits.

- 10 One of the objects of the invention is to provide a fuse plug of simple construction, which may be cheaply manufactured, and which may be made to perform all of the functions of standard devices of this type.
- 15 A further object is to provide a fuse plug having efficient means for maintaining a fuse wire in operative position, in a manner which will permit of its immediate renewal after it has been ruptured. A further object is to provide a fuse plug, the parts of which may be readily removed for inspection and substitution of new parts, as occasion may require.

The invention will be hereinafter fully set forth and particularly pointed out in the claims.

In the accompanying drawing:—

Figure 1 is a side elevation illustrating a fuse plug constructed in accordance with the invention. Figure 2 is a longitudinal sectional view thereof. Figure 3 is a top plan view. Figure 4 is a bottom plan view. Figures 5 and 6 are detail views illustrating modifications of the contact strip. Figures 7 and 8 are longitudinal sectional views illustrating modifications of the fuse plug.

Referring to Figures 1 to 4 of the drawing, 10 designates the body of the plug, which is in the form of a casing constructed of porcelain or other suitable insulating material, closed at one end and open at the other. Enclosing the lower portion of said body, is a screw shell 11, which is held from rotation relative to the body 10, in any desired manner. It is preferred, however, to provide the closed end of the body with a projection 12, which protrudes through a complementary opening in the shell, said projection and opening being shaped to prevent relative rotation. In the drawing the projection 12 is shown as of approximately elliptical form. The portion of the body 10

contiguous to the open end is provided with external screw threads 13, and the wall of said body is provided with a longitudinally disposed channel 14, one end of which terminates at the open end of the body, the other end leading to the outer surface of the body, at a point covered by the shell 11. The closed end of the body is provided with a longitudinally disposed bore 15.

Mounted in the open end of the body 10 is a contact strip 16, preferably in the form of an elongated rectangular plate, provided at one end with a groove in which is soldered, or otherwise secured, one end of a conductor wire 17. Said strip is provided with an opening 18, of polygonal form, and also with a groove 19. The wire 17 extends through the channel 14 and contacts with but is not secured to the shell contact 11, in a manner which will be clearly understood from the drawing. The strip 16 is supported in any suitable manner, preferably resting upon internal shoulders located just inside of the open end of the body 10.

The rupturable fuse strip is preferably in the form of a wire 20, one end of which is coiled around the shank of an anchoring device 21, slidably mounted in the opening 18 of the contact strip 16. The shank is of a cross-section complementary to the opening 18, to prevent relative rotation. Said anchoring member 21 is provided with headed ends, one of the heads 22 being pressed inwardly by a cover plate 23, of insulating material to which clamping pressure is applied by means of an overhanging flange, formed on a screw shell 24, engaging the threads 13. In this manner the wire 20 is clamped between said head 22 and the member 16, to insure a perfect electrical contact. If desired the cover plate may be transparent.

To provide means for indicating when a fuse is burned out, it is preferred to form a hole in the cover plate 23 and to place therein a paper cap C. In the absence of other vents or holes, the heated gases must escape through this hole by pushing out the cap C, thereby providing a very clear and definite indication of a blown fuse.

Rigidly secured in the bore 15, of the closed end of the plug body, is a metal

bushing 25, provided with an outer flange 26. Slidably mounted in said bushing is a tubular anchoring member 27, provided with inner and outer flanges 28 and 29, for 5 limiting its sliding movement, a transverse opening being formed in said member contiguous to the flange 29. The lower end of the fuse wire 20 is passed through the bore of the anchoring member 27, and laterally 10 through the transverse opening therein, the extremity of said wire being wrapped around the anchoring member in a position to come between the flange 26 of bushing 25 and the flange 29 of the anchoring 15 member.

In practice, the inner end of the fuse wire 20 is secured to the anchoring member 27, in the manner above set forth, the other end being engaged with the groove 19 of 20 the anchoring device 21, and engaged with the contact strip 16, in the manner heretofore described. The cover plate 23, and the clamping shell 24, are then secured in position, the clamping pressure produced by 25 said shell serving to force the anchoring member 21 inwardly, causing the fuse wire to be firmly gripped between it and the contact plate 16. The clamping pressure exerted through the anchoring member also 30 retains the contact member in place. The plug is then ready for use and may be engaged with any standard socket, through the medium of the shell 11, the anchoring member 27 serving as the center contact. 35 The circuit will then be completed through anchoring member 27, fuse wire 20, contact plate 16, and conductor wire 17, to shell 11. Should the wire 20 become ruptured from any cause, the plug is first removed from its 40 socket, and clamping shell 24 unscrewed to permit removal of the cover plate 23, which will expose the contact strip 16 and its wire 17. The strip 16 is readily lifted out because the wire 20 has been ruptured and 45 the wire 17 is not attached to the shell 11. After removal of the strip 16, the shank of the anchoring member 21 may then be pressed outwardly to free the contiguous end of the wire 20, and the other end of the 50 said wire may also be disengaged from the anchoring member 27, by moving the latter outwardly to permit of said disengagement. A new wire 20 may then be substituted, and the parts all replaced, the whole operation 55 requiring but very little time, and the plug is again ready for use.

In lieu of providing the contact strip 16 with the polygonal opening and the slideable anchoring member 21, said opening 60 may be circular and provided with internal threads to engage a binding screw 30, around which the end of the wire 20 may be wrapped in a well-known manner. Such a construction is illustrated in Figure 5. 65 Or said plate may be provided with de-

pending legs 31 to retain it in position, as illustrated in Figure 6.

In Figure 7, is illustrated a modified arrangement of the means for establishing the circuit through the fuse wire. In this 70 form, a body 10^a is provided with a channel 14^a, formed with a shoulder 32, which serves as a seat for a contact member 33. One end of said contact member is shaped 75 to engage the shell 11^a, the other end being provided with an enlarged socket 34, shaped to engage said shoulder. The socket 34 receives the shank of a headed anchoring member 35, around which the outer end 80 of the fuse wire 20^a is wrapped, said anchoring member being retained in position by a cover plate 23^a and clamping shell 24^a. The other end of wire 20^a, engages a longitudinal groove in an anchoring member 27^a, having headed ends, the 85 contiguous extremity of the wire being wrapped around the shank of the anchoring member, between the outer head and the end of the casing.

In Figure 8, is illustrated another modification. In this form the casing 10^b is provided with a permanent center contact 36, and a shell contact 11^b. The interior of said body is provided with a contact plate 37, having fingers 38 projecting through the wall of the casing into engagement with the shell 11^b. The fuse wire 20^b is mounted in a supporting frame or contact member 39, provided with an upper anchoring member 21^b, and a lower anchoring member 27^b, the ends of said wire being engaged 100 with said anchoring members. The anchoring members may be of any preferred form, but as illustrated they comprise headed shanks slidably mounted in the frame, and so arranged that the ends of the wire may be clamped between heads thereof and the frame. Said frame is provided with a contact member 40 having resilient portions 41 105 engaging the plate 37, the frame being held upright by frictional engagement of the springs 41 with said plate. The anchoring member 27^b is held against the center contact 36, and the anchoring member 21^b is held clamped against the frame 39, by the 110 cover plate 23^b, which is retained in position by the shell 24^b.

From the foregoing description it will be readily understood that the invention provides a fuse plug of very simple construction, which may be cheaply manufactured, and that the parts are so related that the fuse wire may be quickly renewed when necessary and that other repairs may be made without difficulty.

Having thus explained the nature of the invention and described an operative manner of constructing and using the same, although without attempting to set forth all 125 of the forms in which it may be made, or all 130

of the forms of its use, what is claimed is:—

1. A fuse plug of the character described comprising a casing of insulating material having an internal chamber, a shell contact carried by said casing, a center contact, a contact member in circuit with the shell contact, a fuse wire removably connected at one end to said center contact and extended 10 longitudinally through said chamber, means for anchoring the other end of said wire to said contact member, and means independent of the anchoring means for applying clamping pressure thereto.

15 2. A fuse plug of the character described comprising a casing of insulating material, a shell contact carrier thereby, a center contact, a contact member in circuit with said shell contact, a freely movable anchoring member carried by said contact member, a fuse wire having one end connected to the center contact and the other end clamped between said anchoring member and said contact member, and means independent of 20 the anchoring member for applying clamping pressure thereto.

3. A fuse plug of the character described comprising a casing of insulating material, a shell contact carried thereby, a center contact, a contact member in circuit with said shell contact, an anchoring member carried by said contact member, a fuse wire having one end connected to the center contact and the other clamped between said anchoring member and said contact member, and a cover plate positioned to engage said anchoring member and through it to retain 35 said contact member in place.

4. A fuse plug of the character described comprising a casing of insulating material, a shell contact carried thereby, a center contact, a contact member in circuit with said shell contact, an anchoring member slidably mounted in said contact member and provided with a clamping portion, a fuse wire connected at one end to said center contact and having its other end removably held between said contact member and the clamping portion of the anchoring member, and 45 means for applying a clamping pressure to said anchoring member.

5. A fuse plug of the character described comprising a casing of insulating material, a shell contact carried thereby, a center contact, a contact member in circuit with said shell contact, an anchoring member slidably mounted in said contact member and provided with a clamping portion, a fuse wire connected at one end to said center contact and having its other end removably held between said contact member and the clamping portion of the anchoring member, a cover plate engaging said anchoring member, and means for applying a clamping 55 pressure to said cover plate, whereby said

contact member is retained in place through pressure applied to said anchoring member.

6. A fuse plug of the character described comprising a casing of insulating material, a shell contact carried thereby, a center contact, a contact member in circuit with said shell contact, an anchoring member slidably mounted in said contact member and provided with a clamping portion, a fuse wire connected at one end to said center contact and having its other end removably held between said contact member and the clamping portion of the anchoring member, and removable pressure-applying means positioned to engage the clamping portion of 70 said anchoring member, whereby said contact member is retained in place through pressure applied to the anchoring member.

7. A fuse plug of the character described comprising a casing of insulating material, a shell contact carried thereby, a center contact, a contact member in circuit with said shell contact, an anchoring member of conducting material slidably supported by said contact member and provided with a clamping portion, a fuse wire extending through the casing and directly connected at one end to said center contact and having its other end removably held between said contact member and the clamping portion of the 75 anchoring member, a cover plate positioned to engage the clamping portion of said anchoring member, and a screw shell removably engaging said casing and having means for retaining said cover plate in place.

8. A fuse plug of the character described comprising a casing of insulating material, a shell contact carried thereby, a center contact, a contact member in circuit with said shell contact and provided with an opening of polygonal shape, a headed anchoring member having a shank complementary to and slidably mounted in said opening, a fuse wire connected at one end to said center contact and having its other end engaging said anchoring member, a cover plate for normally preventing sliding movement of the anchoring member, and means retaining said cover plate in position.

9. A fuse plug of the character described comprising a casing of insulating material provided with a chamber and having a channel in its wall leading from said chamber to an opening in the outer surface of the casing, a shell contact covering the said opening, a contact plate in said chamber provided with an extension located in said channel and removably contacting with said shell contact, a center contact, and a fuse wire leading from said center contact to said contact member.

10. A fuse plug of the character described comprising a casing of insulating material provided with a chamber and having a channel in its wall leading from said chamber 125

to an opening in the outer surface of the casing, a shell contact covering the said opening, a contact plate in said chamber provided with an extension located in said channel and removably contacting with said shell contact, an anchoring member mounted in said contact plate, a center contact, a fuse wire connecting said center contact and said anchoring member, and means engaging said anchoring member to retain said contact plate in position.

11. A fuse plug of the character described comprising a casing of insulating material provided with a chamber and having a channel in its wall leading from said chamber to an opening in the outer surface of the casing, a shell contact covering the said opening, a contact plate in said chamber provided with an extension located in said channel and engaging said shell contact, an anchoring member slidably mounted in said contact plate, a center contact, a fuse wire connecting said center contact and said anchoring member, a cover plate positioned to engage said anchoring member, and means for applying a clamping pressure to said cover plate.

12. A fuse plug of the character described comprising a casing of insulating material, a shell contact carried thereby, a contact member mounted in said casing and in circuit with said shell contact, a bushing mounted in one end of said casing, an anchoring member slidably mounted in said bushing and positioned to form a center contact, and a fuse wire having one end connected with said contact member and the other clamped in place by said anchoring member.

13. A fuse plug of the character described comprising a casing of insulating material, a shell contact carried thereby, a contact member mounted in said casing and in circuit with said shell contact, a bushing mounted in one end of said casing, a tubular anchoring member slidably mounted in said bushing and positioned to form a center contact, and a fuse wire having one end connected with said contact member and its other end passed through and clamped by said anchoring member.

14. A fuse plug of the character described comprising a casing of insulating material closed at one end, a shell contact mounted on said casing, an internal contact member in circuit with said shell contact, an anchoring member slidably mounted in said contact member, a second anchoring member slidably mounted in the closed end of the casing and positioned to form a center contact, and a fuse wire having its ends removably engaged by the respective anchoring members.

15. A fuse plug of the character described comprising a casing of insulating material, a shell contact carried thereby, a center

contact, a contact member removable independently of the center contact, a fuse wire having one end connected with the center contact, an anchoring member loosely supported by the contact member and engaging the other end of said wire, and means removable with the contact member for placing it in circuit with the shell contact.

16. A fuse plug of the character described comprising a casing of insulating material, a shell contact carried thereby, a center contact, a contact member removable independently of the center contact, a fuse wire connected with the center contact and the contact member, and means removable with the contact member for placing it in circuit with the shell contact.

17. A fuse plug of the character described comprising a casing of insulating material, a shell contact carried thereby, a center contact, a contact member removable independently of the center contact, and a fuse wire connected with said center contact and said contact member, one end of said contact member having means removable with it for placing it in circuit with the shell contact.

18. A fuse plug comprising a casing of insulating material, a shell contact carried thereby, a center contact, an internal contact member in circuit with the shell contact, a slidable anchoring member loosely supported by said internal contact member, a fuse wire having one end in circuit with the center contact and the other end engaged with said anchoring member, and means normally preventing slidable movement of the anchoring member.

19. A fuse plug comprising a casing of insulating material, a shell contact carried thereby, a center contact, an internal contact member in circuit with the shell contact, a slidable anchoring member loosely supported by said internal contact member, a fuse wire having one end in circuit with the center contact and the other end engaged with said anchoring member, and means removably engaging the casing to maintain a clamping pressure on the anchoring member.

20. A fuse plug of the character described comprising a casing of insulating material provided with a chamber and having a channel in its wall leading from said chamber to an opening in the outer surface of the casing, a shell contact covering the said opening, a center contact, a fuse wire having one end in circuit with said center contact, a loosely supported anchoring member to which the other end of said wire is connected, and a conductor member located in said channel and in circuit with said anchoring member and said shell contact.

21. A fuse plug comprising a casing of insulating material, a shell contact carried

thereby, a center contact, an internal contact member in circuit with the shell contact, a conductor extending through the wall of the plug and in circuit with said shell and slidable anchoring member, a fuse wire having one end in circuit with the center contact and the other end engaging said

anchoring member, and means normally preventing slidable movement of the anchoring member.

In testimony whereof I have hereunto set my hand.

LUIGI VECCHIO.
